ATTORNEY

UNITED STATES PATENT OFFICE.

CHARLES WEISSE, OF BROOKLYN, NEW YORK.

GAME APPARATUS.

Application filed February 11, 1928. Serial No. 253,583.

This invention relates to a game apparatus with which a person may exercise his or her skill in the art of throwing.

The principal object of the invention is 5 the provision of an apparatus enabling a person to throw an allotted number of balls at a target simulating a head of a natural object having teeth in an opening, with the idea of knocking out as many teeth as possible with the allotted number of balls, and incidentally win a suitable prize offered.

The nature of the invention and its distinguishing features and advantages will appear when the following specification is read 15 in connection with the accompanying drawing, in which—

Figure 1 is a front view of the target of the apparatus.

Fig. 2 is a vertical sectional view taken on 20 the line 2—2 of Fig. 1.

Fig. 3 is a rear view of the target.

Figs. 4 and 5 illustrate different views of one of the teeth of the target.

The game apparatus of the present invention 25 includes a target 10 which may be supported in any suitable manner; it may either be fixed on a suitable support or it may be suspended therefrom for swinging movement.

30 It is to be understood that the target will be arranged at a predetermined distance from a point at which a person will pitch or throw an allotted number of balls (not shown) which will form a part of the apparatus at the target 10 for a purpose to be explained. The target 10 in the present instance is made in simulation of a head of a natural object, and may be diversely formulated. In the present instance the target 10 includes a rigid base member 11 which is cut 40 and formed to provide the desired outline and an opening representing a mouth opening. The base member 11 has arranged on one face thereof padding 12 held in place by a suitable covering material 13, such as 45 leather or stout canvas, or any other suitable material. The covering material 13 will be secured along its marginal edges in any suitable manner to the base member 11. On the front surface of the covering material 13

50 will be painted or otherwise produced eyes and a nose to complete a face. The mouth opening is designated 14. Suitable elements 55 constituting teeth are provided and each is adapted to be associated with the base member 11 so as to extend or project into or

adjacent the opening 14. Each element 15 may be made of any preferred material such as wood with a suitable pad 16 on one end and notches 17 respectively in opposite sides 60 near the opposite end of the element. The opposing walls of each notch are preferably rounded or curved in opposite directions. Each element 16 thus constructed is adapted to be supported by suitable pins 18 or the like extending laterally at an angle from the base member 11. A pair of pins 18 is employed in conjunction with each element 15, the pins of each pair being respectively received in the notches 17, as shown most 70 clearly in Figs. 2 and 3. In this way a plurality of the elements or teeth 15 may be arranged to extend or project into or adjacent the mouth opening 14 to be knocked from their pins by being struck with a thrown ball. 75

The following rules must be observed in playing the game which is to be known as Knock em out.

Each player is allotted three balls.

The player must endeavor to knock teeth 80 out of mouth opening.

The player must endeavor to knock out all of the teeth with as few balls as possible to entitle the player to the best prize.

When all teeth are knocked out by a player 85 with one, two or three balls the game is over.

It is to be understood that the target may be in simulation of the head and face of any type of natural object, human or animal types; that any suitable number and arrangement of teeth may be provided; and that the sizes and relative disposition of the parts may be varied, as well as the construction thereof.

I claim:

1. In a game apparatus, a target made in simulation of a head of a natural object and having a mouth opening, elements constituting teeth, each of said elements having notches therein, each element being supported 100 to project into or adjacent the mouth opening by means on the target which extends into the notches, and each element so supported being capable of being knocked off said means by a missile thrown through said 105 mouth opening.

2. In a game apparatus, a target made in simulation of a head of a natural object and having a mouth opening, elements constituting teeth, each of said elements having 110 notches therein, each element being supported to project into or adjacent the mouth

opening by pins on the target which extend respectively into the notches, and each element so supported being capable of being knocked off said pins by a missile thrown through said mouth opening.

3. In a game apparatus, a target having an opening therein, elements each having a padded end and provided with notches in the opposite side edges, and means on the target on the rear thereof receivable in the

notches of each of said elements to support it in position with its padded end disposed to be hit by a ball or the like through said opening and thus knock the element off said means.

Signed at New York, in the county of New York and State of New York, this 9th day of February, 1928.

CHARLES WEISSER.
